UNITED STATES PATENT OFFICE.

ARTHUR B. HANSEN, OF NEW YORK, N. Y.

APPARATUS FOR SUBMARINE WORK.

1,425,471.

Specification of Letters Patent.

Patented Aug. 8, 1922.

Application filed April 14, 1920. Serial No. 373,752.

To all whom it may concern:

Be it known that I, ARTHUR B. HANSEN, a citizen of the United States, and a resident of the city of New York, borough of 5 Manhattan, and county and State of New York, have invented a new and Improved Apparatus for Submarine Work, of which the following is a full, clear, and exact description.

10 This invention relates to an apparatus for submarine work.

While many devices of this character have been proposed, they have been found objectionable and impractical due to the complex 15 and complicated nature of their construction and operation.

The primary object therefor of the present invention is to provide an apparatus of this character which is simple in its 20 construction, effective in purpose and readily operable by persons of ordinary intelligence and mechanical ability.

Another object of the invention is to provide an apparatus which is designed primarily 25 to form an important element of a ship's complement which is capable of use in cleaning or repairing submerged portions of the hull, without resorting to the use of expensive diving apparatus.

30 The device is also especially useful on oil tankers where it is necessary for a man to descend into the filled tanks to repair broken pipe connections or work of a similar nature.

35 A further object of the invention is to provide a device of the character described which permits of ready communication between the submerged workman and others at the surface.

40 A still further object of the invention is to provide an apparatus of the character described which is so constructed as to render ingress and egress therefrom an extremely simple and expeditious operation.

45 With the above recited and other objects in view, some of which will be more readily apparent hereafter, reference is made to the following description and claims and the accompanying drawings which form a part of 50 the application.

In the drawings;

Figure 1 is a transverse sectional view through the hull of a vessel illustrating the use and application of the device.

55 Figure 2 is an enlarged fragmentary side

view thereof with parts in section to disclose the underlying structure.

Figure 3 is a front elevation of the same.

Figure 4 is a transverse sectional view through the apparatus taken approximately 60 on the line 4-4 of Figure 2.

Figure 5 is a fragmentary enlarged sectional view of the upper portion of the flexible extension.

Referring to the drawings by characters 65 of reference which denote like parts throughout the several views thereof, H represents the hull of a vessel and D a davit from which the apparatus illustrated is de-

signed to be suspended. The apparatus in- 70 cludes a waterproof suit 10 constructed of canvas, rubberized cloth or any other suit- able waterproof material which is flexible.

The suit 10 is provided with legs 11 and 75 feet 12 which are preferably weighted for the purpose of readily effecting submersion.

The suit is further provided with arms 13 and the body portion 14 of the suit is formed with an upper open tubular collar 15. The 80 collar 15 which houses the head of the work-

man when in the suit is provided with a sight opening covered by a transparent panel 16. Secured to the upper open end of the collar or formed as a continuation there- 85

of is a tubular extension 17 which is also 90 constructed of flexible waterproof material. The said extension 17 is of a sufficient length

to reach from the bottom of the hull to the deck of the vessel. In order to hold the 95 extension 17 extended when submerged, the same is provided with a plurality of vertically spaced rigid annular members 18 se- 100

cured to the interior thereof. The extreme upper and lower members 18 are connected by the cables 19 secured thereto at diametri- 105

cally opposed points. The remaining mem- bers 18 are provided with eyes 20 at diametrically opposed points on their inner 110 peripheries, through which the cables 19 are

passed to reduce the possibility of twisting of the extension to a minimum. The cables 19 also serve to prevent stretching of the ex- 115

tension and assist in bearing the strain of the workman's weight on the extension. A hoisting cable 21 is attached to a bail or 120

harness 22 secured to the upper member 18 and said cable 21 is designed to be passed over a pulley on the davit or other suitable 125

supporting member.

In order to provide means for retaining 130

the workman stationary with relation to his work when submerged, an auxiliary supporting and steadyng cable 23 is provided which is attached to a belt 24 embracing the body portion 14 of the suit 10, the opposite ends of the cable respectively leading up to a pulley on the davit and around under the hull where the extreme end is made fast to a cleat on the opposite side of the deck.

10 From the foregoing construction it will be seen that the upper open end of the extension is designed to be arranged along side the deck in order that communication may be had with the submerged workman to give 15 proper instructions and receive orders as the case may be.

While the device is especially adapted and intended for submarine work, no limitation is made to this use nor to the precise design 20 of construction exhibited, but it is to be understood that such changes and alterations as fall within the scope of the appended claim may be resorted to when found expedient.

25 Having thus described my invention, what

I claim as new and desire to secure by Letters Patent, is,

An apparatus for submarine work including a waterproof suit having an open upper end and a continuous flexible and collapsible tubular extension communicating with said upper end, spaced annular braces secured within said extension that maintain the same distended when submerged, a flexible connection between the upper and lowermost braces constituting a means for limiting the relative separation of said upper and lowermost braces whereby the weight of the suit and diver is supported by the flexible connection, the intermediate 40 braces having eyes through which said connection is trained to prevent relative twisting of the braces and the extension, a belt secured around the intermediate portion of the suit, and a forwardly presented eye carried by the belt adapted to receive the intermediate portion of an adjustable hauling line.

ARTHUR B. HANSEN.
